STAPLING MACHINE

Max Vogel, Frankfort-on-the-Main, Germany

Application November 2, 1933, Serial No. 696,398
In Germany September 1, 1933

14 Claims. (Cl. 1-3)

This invention relates to new and useful improvements in stapling machines:

An object of the invention is to provide a stapling machine including improved staple clinching means whereby staples will have their prongs bent and flattened against the underside of the article or articles through which they are driven.

Another object is to provide a stapling machine including an improved guide or gauge for determining the place at which a staple will be driven into an article by the machine.

Other objects and advantages will become apparent from a consideration of the following detailed description taken in connection with the accompanying drawing wherein a satisfactory embodiment of the invention is shown. However, it will be understood that the invention is not limited to the details disclosed but includes all such variations and modifications as fall within the spirit of the invention and the scope of the appended claims.

In the drawing:

Fig. 1 is a view partly in side elevation and partly in section showing a stapling machine constructed according to the present invention;

Fig. 2 is a top plan view on an enlarged scale and showing the forward portion of the base of the machine;

Fig. 3 is a front elevational view of the base of the machine;

Fig. 4 is a sectional view taken substantially along the line 4-4 of Fig. 2, the parts being in normal position;

Fig. 5 is a similar view showing the anvil means and the support and locking means therefor depressed as at the end of a stapling operation;

Fig. 6 is a front elevational view of the lower portion of the machine, portions being broken away and showing the parts in the positions occupied by them at the end of the initial operation or movement of the machine;

Fig. 7 is a view similar to Fig. 6 but showing the changes in the position of the parts as the driving operation progresses;

Fig. 8 is a similar view showing the parts in their relative positions at the end of the driving operation;

Fig. 9 is a transverse sectional view through the base of the machine and showing the mounting for the guide or gauge; and

Fig. 10 is a top plan view of Fig. 9.

Referring in detail to the drawing, at 10 is generally indicated the body or housing of a stapling machine. This body may be of any desired construction and include any suitable means for

feeding and driving staples. As here shown, body 10 is pivotally secured to an end portion of a base 11 as at 12, it being pivoted between spaced upwardly extending ears 12a cut and struck up from the sheet metal base 11, and includes a guide bar 13 along which staples 14 are fed as by a follower 15 urged along the bar by a spring 16. As is usual in these constructions the staples, usually as a strip in which the staples are secured together by solder or cement, are fed one at a time into a raceway through which they are driven by a plunger 17 arranged to be operated by a hand piece 18 normally held elevated by a spring 18a. It will be understood that the staple driving means is located in the head 20 forming the forward portion of the body 10. The forward portion of the guideway for the plunger or raceway through which the staples are driven by the plunger may be closed by a removable front wall in the form of a plate 20a having notches 20b in its lower edge to receive threaded studs 20c carrying clamping nuts 20d threaded onto the studs. By loosening the nuts or clamps 20d the plate 20a may be lifted from the studs 20c to expose the lower portion of the raceway and forward end of staple strip guide 13.

On the base 11 beneath the head 20 of the staple driving means is an anvil means 21. To accommodate this anvil means an opening 22 is formed in the base 11 and to the under side of the base there is secured a plate 23 between which and the base there is shown interposed a filler plate 24. The rear portion of plate 23 may be of added thickness in which event the plate 24 could be omitted. Rivets 25 rigidly secure the plates 23 and 24 to the base and while the plate 24 stops short of an edge of the opening 22 the plate 23 is lanced and has its forward central portion 26 extending across said opening at the lower side thereof and has its forward edge portions extending upwardly through said opening and forming lugs 27.

Mounted on the upwardly extending plate portions or lugs 27 is a support 28 in the form of a cross sectionally inverted U-shaped member and this support straddles the lugs 27 and is secured to them by pins or rivets 29 connecting the side portions of the support and passing through slots 30 in the lugs whereby the support is mounted for limited movement through the opening 22 in the base. In its connecting or top portion the support 28 is provided with an opening 31 (see Fig. 2) the purpose of which will later fully appear.

Mounted in the support 28 between the lugs 27 is a pair of anvil members 32 each somewhat

L-shaped. These members are arranged opposite each other and each has the end of one of its arms pivoted to the support as at 33. When the anvil members are positioned as in Fig. 6 they 5 are in their normal or inoperative positions and it will be noted that their curved heel or cam portions 34 are in engagement with the forward portion 26 of the plate 23 and that their free end portions 35, which form the anvil, are at opposite 10 sides of the opening 31 in the outer wall or connecting portion of the support.

A generally U-shaped spring 36 has its arm 37 secured against the underside of the forward portion of the base as by a bolt 38 and the arm 39 15 of this spring extends rearwardly at the upper side of the base and through an opening 40 in the support 28. Normally the arm 39 of the spring is disposed against the support 28 at the upper side or edge of the opening 40 therein and 20 when in this position is disposed between the free ends of the anvil members as best shown in Fig. 6.

When the spring is so positioned it is urging the support 28 outwardly or upwardly to the limit of its movement so that the pins 29 are in the 25 upper ends of the slots 30 in the lugs 27. Further, the heel portions 34 of the anvil members are in engagement with or just above plate 23 and the outer surfaces of said members are against the lugs 27. Therefore, the anvil members are 30 held against movement away from each other about their pivots 33 and since the spring arm 39 is between their free end portions or walls 35a they cannot move toward each other. From this it will be understood that when the parts are as 35 in Fig. 6 the support 28 and the anvil members 32 are locked against movement downwardly toward the base 11 by the spring 39 being located between the ends or shoulders 35a of anvils 32 as it prevents the free ends 35 of these anvils 40 moving toward each other, which they must do if the support 28 moves downwardly because the anvils are pivoted to the support at 33 and their cam portions 34 engage the top of plate 26.

Now assuming that papers P are to be stapled 45 together. These papers are placed on the support 28 as shown and the hand piece 18 is pressed. This causes a movement of the body 10 about its pivot 12 to bring the head 20 against the papers P on the support. The locations of the parts is 50 such that when head 20 is against the support 28 the raceway in such head is opposite or in alignment with the opening 31 in the outer wall or connecting portion of the support. It will therefore be clear that the parts of the papers P 55 through which a staple 14 is to be driven are over the opening 31 and that driving the free ends of the staple prongs through the paper does not take place with the prongs against an anvil.

With the parts positioned as above described 60 (papers P being on the support and head 20 being against the paper) further pressure on the hand piece 18 results in a staple being forced along the raceway while the support 28 remains stationary with the anvil members locked in inoperative position. Under these conditions the 65 prongs of the staple are forced through the portions of the papers P over the opening 31 and after passing through the papers the prongs pass through the opening 31 to engage the arm 39 of spring 36 as shown in Fig. 6. It is particularly noted that the staple prongs do not engage the 70 spring arm 39, which arm constitutes a locking means for the anvil members, until after such prongs have passed through the articles to be 75 stapled, and therefore the support 28 is held in

its upper position and supports the papers in this position until the prongs of the staple pass through the papers.

As the operation of driving the staple continues 5 the spring arm 39 is forced downwardly as shown in Fig. 7 by pressure from the prongs of the staple and moves from between the free end portions of the anvil members. Inwardly of their free end portions the anvil members are curved on their inner edges providing cam surfaces 41 and as the 10 spring arm 39 is moved downwardly by pressure of the staple prongs the anvil members are released so they are free to swing toward each other.

Therefore as the stapling operation continues 15 the pressure of head 20 on support 28 causes the latter to move downwardly since the anvil members are no longer held against movement. As the support moves downwardly it carries the pivot pins 33 downwardly with the result that the anvil 20 members cam on their heel portions 34 against plate 26 and their free ends move inwardly toward each other. During movement of the anvil members toward one another they engage the outer sides of the lower or inner portions of the 25 staple prongs and fold such prongs toward one another and upwardly toward the under side of papers P.

When the anvil members reach the positions 30 in which they are shown in Fig. 8 the support 28 is against the forward tongue portion 26 of plate 23 and so is rigidly held and the anvil members are likewise rigidly held, and as the final pressure is applied to the hand piece 18 the plunger 17 is forced to the limit of its movement with the result 35 that the staple is clinched with its prongs flat against the papers or other articles as in Fig. 8.

In this figure and in Fig. 5 it will be noted 40 that the spring arm 39 is a short distance above the lower edge of opening 40. The spring is moved to this position by engagement with the cam surfaces 41 of the anvil members as the latter moves to operative position, in which position they are shown in Fig. 8. At the conclusion of 45 the stapling operation pressure on the hand piece 18 is released and spring 18a raises the plunger. As the body 10 is swung upwardly the support 28 is released and the spring 36 acting through its arm 39 elevates the support 28 to normal position and returns the anvil members to inoperative 50 position by riding upwardly on curved cam surfaces 41 and engaging top edge of opening 40, and locks them in such position ready for the next stapling operation.

From the foregoing it will be clear that with 55 the present arrangement of parts a staple is driven through a portion of articles to be stapled located over an opening and does not encounter any serious resistance to movement of its prongs. However, when the prongs are through the articles they release a locking means whereby the anvil members come into operation and turn over the staple prongs whereby they are clinched flat against the articles being stapled.

A limiting or gauge means is mounted on the base 11 and to this end the longitudinal edge portions 42 of the base are bent up to form channels 43 in which are disposed the arms 44 of a gauge or limiting means 44. Means 44 extends transversely of the base and includes an intermediate portion 45 and a pair of upstanding portions 46 which straddle the lower portion of the housing or body 10 when it is lowered about its pivot.

With its arms 43 in the channels 42 the gauge 75

44 may be shifted or adjusted longitudinally of the base or toward and from the anvil means. In the stapling operation the inner edges of papers or other articles may be placed against 5 the portions 46 of means 44 whereby to determine the place at which staples will be driven into the articles. When the gauge is properly adjusted a series of similar articles may all be stapled at the same distance inwardly of an edge. 0 While the gauge 44 is shown as formed of a single length of round wire it will be understood that it is not limited to such construction. Since the channels 42 are at the outer longitudinal edges of the base and below the center portion thereof it is clear that the base rests on the lower surfaces of these channel portions and a relatively wide base is therefore provided. The transversely extending portion of the gauge is bent downwardly at 45 to accommodate the body 0 10 of the stapling means during a stapling operation. The base 11 is preferably a strip of sheet metal of heavy gauge, and it will be apparent that the downwardly, outwardly and upwardly bent edge portions 47 materially strengthen and stiffen this base so that it is not readily bent out of shape.

Having thus set forth the nature of my invention, what I claim is:

1. In a stapling machine including a base and staple driving means movable toward and from the base, a pair of anvil members, means mounting said anvil members on the base for movement between operative and inoperative positions, locking means normally holding said anvil members in inoperative position, said locking means positioned to be released by the pressure of the prongs of a staple being driven, and means outwardly of said locking means and forming a support for articles to be stapled whereby the 0 prongs of a staple release said locking means after passing through the articles being stapled.
2. In a stapling machine including a base and staple driving means movable toward and from the base, a pair of anvil members, means pivotally mounting said members on the base for pivotal movement between operative and inoperative positions, locking means normally occupying a position maintaining said anvil members in inoperative positions, said locking means normally positioned to be engaged by the prongs of a staple being driven and moved out of locking position to permit said anvil members to move to operative position, and means outwardly of said locking means and forming a support for articles to be stapled whereby the 5 staple prongs engage and move said locking means after passing through the articles being stapled.
3. In a stapling machine including a base and staple driving means movable toward and from the base, a pair of anvil members, means pivotally mounting said members on the base for pivotal movement between operative and inoperative positions, locking means normally maintaining said anvil members in inoperative positions, said locking means positioned to be released by the prongs of a staple being driven and permit said anvil members to move to operative position, and means outwardly of said locking means and forming a support for articles to be stapled 0 whereby the staple prongs release said locking means after passing through the articles being stapled.
4. In a stapling machine including a base and staple driving means movable toward and from the base, a pair of anvil members, means mount- 5 ing said members on the base for movement between operative and inoperative positions, locking means normally occupying a position maintaining said anvil members in inoperative position, said locking means normally positioned to be engaged by the prongs of a staple being driven and moved out of locking position to permit said anvil members to move to operative position, and means outwardly of said locking means and forming a support for articles to be stapled 10 whereby the staple prongs engage and move said locking means after passing through the articles being stapled.
5. In a stapling machine including a base and staple driving means movable toward and from the base, a pair of anvil members, means pivotally mounting said members on the base for pivotal movement between operative and inoperative positions, locking means comprising a spring arm normally occupying a position maintaining said anvil members in inoperative positions, said spring arm normally positioned to be engaged by the prongs of a staple being driven and moved out of this position to permit said anvil members to move to operative position, and means outwardly of said spring arm and forming a support for articles to be stapled 15 whereby the staple prongs engage and move said spring arm after passing through the articles being stapled.
6. In a stapling machine including a base and staple driving means movable toward and from the base, a pair of anvil members, means pivotally mounting said members on the base for pivotal movement between operative and inoperative positions, locking means comprising a spring arm normally occupying a position between and maintaining said anvil members in inoperative positions, said spring arm normally positioned to be engaged by the prongs of a staple being driven and moved out of position 20 between said anvil members to permit them to move toward each other to operative position, and means outwardly of said spring arm and forming a support for articles to be stapled 25 whereby the staple prongs engaged and move said spring arm after passing through the articles being stapled.
7. In a stapling machine including a base and staple driving means movable toward and from the base, a pair of anvil members, means mounting said anvil members on the base for movement between operative and inoperative positions, locking means normally between and holding said anvil members in inoperative position, said locking means positioned to be moved to 30 released position by the pressure of the prongs of a staple being driven whereby said anvil members may move to operative positions, and means outwardly of said locking means and forming a support for articles to be stapled whereby the 35 prongs of a staple release said locking means after passing through the articles being stapled.
8. In a stapling machine including a base and staple driving means movable toward and from the base, a pair of anvil members, means mounting said anvil members on the base for movement between operative and inoperative positions, locking means comprising a spring arm normally between and holding said anvil members in inoperative position, said spring arm positioned to be moved to released position by the 40 pressure of the prongs of a staple being driven whereby said anvil members may move to operative positions, and means outwardly of said spring arm and forming a support for articles to be stapled 45
9. In a stapling machine including a base and staple driving means movable toward and from the base, a pair of anvil members, means mounting said anvil members on the base for movement between operative and inoperative positions, locking means normally between and holding said anvil members in inoperative position, said locking means positioned to be moved to released position by the pressure of the prongs of a staple being driven whereby said anvil members may move to operative positions, and means outwardly of said locking means and forming a support for articles to be stapled 50
10. In a stapling machine including a base and staple driving means movable toward and from the base, a pair of anvil members, means mounting said anvil members on the base for movement between operative and inoperative positions, locking means normally between and holding said anvil members in inoperative position, said locking means positioned to be moved to released position by the pressure of the prongs of a staple being driven whereby said anvil members may move to operative positions, and means outwardly of said locking means and forming a support for articles to be stapled 55
11. In a stapling machine including a base and staple driving means movable toward and from the base, a pair of anvil members, means mounting said anvil members on the base for movement between operative and inoperative positions, locking means comprising a spring arm normally between and holding said anvil members in inoperative position, said spring arm positioned to be moved to released position by the pressure of the prongs of a staple being driven whereby said anvil members may move to operative positions, and means outwardly of said spring arm and forming a support for articles to be stapled 60
12. In a stapling machine including a base and staple driving means movable toward and from the base, a pair of anvil members, means mounting said anvil members on the base for movement between operative and inoperative positions, locking means comprising a spring arm normally between and holding said anvil members in inoperative position, said spring arm positioned to be moved to released position by the pressure of the prongs of a staple being driven whereby said anvil members may move to operative positions, and means outwardly of said spring arm and forming a support for articles to be stapled 65
13. In a stapling machine including a base and staple driving means movable toward and from the base, a pair of anvil members, means mounting said anvil members on the base for movement between operative and inoperative positions, locking means comprising a spring arm normally between and holding said anvil members in inoperative position, said spring arm positioned to be moved to released position by the pressure of the prongs of a staple being driven whereby said anvil members may move to operative positions, and means outwardly of said spring arm and forming a support for articles to be stapled 70
14. In a stapling machine including a base and staple driving means movable toward and from the base, a pair of anvil members, means mounting said anvil members on the base for movement between operative and inoperative positions, locking means comprising a spring arm normally between and holding said anvil members in inoperative position, said spring arm positioned to be moved to released position by the pressure of the prongs of a staple being driven whereby said anvil members may move to operative positions, and means outwardly of said spring arm and forming a support for articles to be stapled 75

be stapled whereby the prongs of a staple release said spring arm after passing through the articles being stapled.

9. In a stapling machine including a base and a staple driving means movable toward and from the base, a support on said base, means mounting said support on the base for movement toward and from the base, a pair of anvil members, means pivotally mounting the anvil members on said support with a portion of each anvil member in engagement with the base, said anvil members movable on their pivots between operative and inoperative positions, locking means releasable by the pressure of the prongs of a staple being driven, said locking means disposed inwardly of the outer edge of said support and normally locking said anvil members in inoperative position, said staple driving means including a head to press against said support during the operation of driving a staple, said anvil members when locked in inoperative positions serving to maintain said support in its outermost position against the pressure of said head, said support adapted to have articles to be stapled placed against its outer edge whereby the prongs of a staple do not release the locking means until such prongs have passed through the articles being stapled, and said anvil members when released adapted to be rocked to operative position as said support is moved by the pressure of said head.

10. In a stapling machine including a base and staple driving means movable toward and from the base, a support, means mounting the support on the base for movement toward and from the latter, said support having an opening through its outer side and through which the prongs of staples may be driven by said staple driving means, a pair of anvil members pivotally mounted in said support, means normally locking said anvil members in a spread apart inoperative position, said locking means positioned to be engaged by the prongs of a driven staple and moved to release said anvil members, said staple driving means including a portion to thereafter shift said support and rock said anvil members on their pivots to bend over the staple prongs and into positions whereby said staple prongs may be clinched against articles on the support.

11. In a stapling machine including a base and staple driving means movable toward and from the base, a support, means mounting the support on the base for movement toward and from the latter, said support having an opening through its outer side and through which the prongs of staples may be driven by said staple driving means, a pair of anvil members pivotally mounted in said support, means normally locking said anvil members in a spread apart inoperative position, said locking means comprising a spring arm positioned to be engaged by the prongs of a driven staple and moved to release said anvil members, said staple driving means including a portion to thereafter shift said support and rock said anvil members on their pivots to bend over the staple prongs and into positions whereby said staple prongs may be clinched against articles on the support, and

said spring operative to return said support and anvil members to normal position on the completion of a staple driving operation.

12. In a stapling machine including a base and a staple driving means movable toward and from the base, a support on said base, means mounting said support on the base for movement toward and from the base, a pair of anvil members, means pivotally mounting the anvil members on said support with a portion of each anvil member in engagement with the base, said anvil members movable on their pivots between operative and inoperative positions, locking means releasable by the pressure of the prongs of a staple being driven, said locking means comprising a spring arm disposed inwardly of the outer edge of said support and normally locking said anvil members in inoperative position, said staple driving means including a head to press against said support during the operation of driving a staple, said anvil members when locked in inoperative positions serving to maintain said support in its outermost position against the pressure of said head, said support adapted to have articles to be stapled placed against its outer edge whereby the prongs of a staple do not release the locking means until such prongs have passed through the articles being stapled, said anvil members when released adapted to be rocked to operative position as said support is moved by the pressure of said head, and said spring operative to return said support and anvil members to normal position on the completion of a staple driving operation.

13. In a stapling machine including a base and staple driving means movable toward and from the base, an upright support mounted for limited up and down movement on the base under the staple driving means, a pair of anvils mounted for movement toward each other to bend the staple prongs and operated by downward movement of the support, and a spring having an arm normally holding the support in its upper position and lying between the anvils to lock them in separated relation, and said arm when in this position being located under the staple driving means in position for the prongs of the staple to engage and move the arm downwardly to release the anvils.

14. In a stapling machine including a base and staple driving means movable toward and from the base, an upright support mounted for limited up and down movement on the base under the staple driving means, a pair of anvils pivotally mounted in the support and movable toward each other to bend the staple prongs, said anvils having cam means co-operating with the base to operate the anvils on movement of the support toward the base, a spring having an arm extending between the anvils and tending to lift the support to its upper position, said arm when in the upper position lying between the free ends of the anvils to lock them in separated relation, and said arm when in this position being located under the staple driving means in position for the staple prongs to engage and move the arm downwardly to release the anvils.

MAX VOGEL.
